TABLE

Filed April 28, 1928

UNITED STATES PATENT OFFICE

JOHN N. FARIS, OF PORTLAND, OREGON

TABLE

Application filed April 28, 1928. Serial No. 273,559.

This invention relates generally to the art of furniture making, and particularly to a folding table.

The first object of this invention is to make 5 a simple and efficient table especially adapted for use with invalids confined to their beds.

The second object is to so construct the table that its top can be easily inclined to 10 various angles to suit the convenience of the user.

The third object is to so construct the table that it will be extremely rigid when set up and will fold into a very compact 15 form.

These, and other objects, will become more apparent from the specification following as illustrated in the accompanying drawing, in which:

20 Figure 1 is a perspective view of the table. Figure 2 is a longitudinal section of the table showing one leg folded and the other extended. Figure 3 is a transverse vertical section taken along the line 3—3 in Figure 2. 25 Figure 4 is a horizontal section taken along the line 4—4 in Figure 2. Figure 5 is an enlarged section taken along the line 5—5 in Figure 2. Figure 6 is an enlarged section through the latch for the table top.

30 Similar numbers of reference refer to similar parts throughout the several views.

Referring in detail to the drawing, the table consists of a pair of sides 10 preferably cut away along their lower edges to 35 form the legs 11, and having blocks 12 secured to each inwardly upper corner. Across the top of the sides 10 is placed a shelf 13 under whose outer edges are secured the cleats 14 whose middle portion is provided with notches 15. Under the middle 40 of the front and rear edges of the shelf 13 are secured the clips 16 which hold the spring rods 17, whose ends 18 are inturned and enter holes 18—A. The tops 12—A of 45 the blocks 12 are bevelled slightly to fit the under side of the shelf 13 when the sides 10 slope outwardly and the inside of the top edge thereof touches the cleat 19.

The cleats 19 are secured to the shelf 13 50 and touch the inner side of the member 10

when the table is in a set-up position. The cleats 14 project forwardly from the shelf 13 and have secured to their projecting ends by means of the hinges 20 a table top 21 around which is formed a rim 22. The under 55 side of the top 21 is provided with hinged braces 23 whose inturned ends 24 can engage any of the notches 15 for the purpose of holding the top 21 at the desired slope.

The spring catch 25 is secured to the under 60 side of the rear edge of the top 21 and is perforated to receive the pin 26. A clip 16 may be permitted to extend beyond the edge 27 and the catch 25 itself may be curved 65 to receive the projecting end.

Obviously, many other forms of catches or fastening means may be employed between the top 21 and the shelf 13 without departing from the spirit of this invention.

In operation if it is desired to set up the 70 table it is only necessary to swing the legs 11 to the position shown in Figure 1 where they will be held by the spring rods 17 which, while acting as hinges, also serve to hold the bevelled faces 12—A firmly against 75 the under side of the shelf 13. When the latch 25 is released the top 21 may be inclined to the desired slope, where it will be held by the braces 23.

I claim:

A table having a top provided with cleats secured to the under side of two opposite edges, a pair of legs for supporting said table, each of said legs having a pair of cleats secured to its upper innermost corners, 85 a pair of springs secured to the under side of said table top having inturned ends journaling in said leg cleats in a manner to form a yieldable pivotal support therefor, and a stop cleat adjacent each table top cleat 90 adapted to engage the inner side of its respective leg when in a table supporting position.

JOHN N. FARIS.
